FUSE CLIP DEVICE

Harold H. McMahon, Pasadena, Calif., assignor
to Illinois Tool Works, Chicago, Ill., a corpora-
tion of Illinois

Application March 4, 1950, Serial No. 147,706

1 Claim. (Cl. 173—328)

1

This invention relates generally to a fuse clip device and relates more specifically to a unitary clip for engaging and retaining the end of an elongated tubular fuse.

In automotive electric circuits, it is common practice to utilize elongated tubular fuses which can be readily inserted between a pair of clips and can be as readily removed. It has been common practice to manufacture the clips for holding such fuses in four parts. A clip portion for gripping the periphery of a fuse adjacent to the end has been provided as a single part. A flange has been provided for positioning adjacent the clip portion to abut against the end of the fuse to prevent longitudinal movement of the fuse, and both the flange and clip portion have been secured to a body or mounting base by a rivet or the like. Such four-piece construction requires considerable assembly time and is unnecessarily expensive. Ultimately the connection between the clip and mounting base becomes corroded and a poor and unreliable electrical contact is made.

A principal object of this invention is the provision of a unitary fuse clip device which insures a good and enduring electrical contact.

Another object of this invention is the provision of a fuse clip device which can be more economically manufactured than those heretofore known in the art.

Other objects and advantages of the present invention will be apparent from the following description when taken in conjunction with the accompanying drawings in which:

Fig. 1 is a side view of my fuse clip device as applied to an automobile generator;

Fig. 2 is an exploded perspective view of my fuse clip device;

Fig. 3 is a sectional view as taken along the longitudinal axis of the fuse;

Fig. 4 is a sectional view taken at right angles to the view in Fig. 3 and also along the longitudinal axis of the fuse;

Fig. 5 is a perspective view of the fuse clip for securing one end of the fuse;

Fig. 6 is a perspective view of the fuse clip for securing the other end of the fuse.

The fuse clip device as shown in Fig. 1 is secured to an automobile generator 8 along with a box 10 by means of a suitable bracket 12. The box may contain a relay or other electrical equipment. As may be seen in Figures 2-4, the fuse clip device comprises an upper clip 14 and a lower clip 16 which are shown in detail in Figures 5 and 6 respectively. Each clip is of unitary integral construction, and is constructed of sheet

metal, preferably Phosphor bronze which has optimum qualities of electrical conductivity and mechanical strength. The upper clip 14 comprises a body portion 18 which is provided near its upper end with a screw receiving aperture 20. The surface of the body portion 18 adjacent to the aperture 20 is dished out as at 22 and is provided with a slot 24 so that the edge of the aperture may be helical in shape to receive and retain a screw which may connect a lead wire 25. A similar aperture 26 is provided adjacent to the lower end of the body portion 18 to receive a mounting screw as will be apparent later. A pair of fingers 28 extend from the sides of the body portion adjacent to the lower end thereof and generally normal to the body portion. Each of the fingers extends traversely a short distance from the body portion before being bent normal thereto to form a curved shoulder 30. Each finger then curves inwardly to form a shoulder 32 and extends outwardly again away from the body portion in a substantially cylindrical fuse gripping portion 34 and is terminated in a reversely bent cam surface 36.

From the top of each cylindrical portion 34 a flange 38 extends toward the other cylindrical portion to form abutment means. From the extreme lower edge of the body portion 18, a locating finger 40 (Fig. 3) extends normally to the body portion and in the opposite direction from the fingers 28 to help determine the position of the clip when it is mounted as will be apparent hereinafter.

The lower clip 16, as may be seen in Figure 6, comprises a body portion 42 of sheet metal and is provided with an aperture 44 for receiving a mounting screw and with a nub 46 which helps to determine the mounting position of the clip. The body portion comprises a piece of sheet metal, the majority of which is flat. The body portion is provided with a substantially U-shaped offset 47 which terminates in a section 48 displaced somewhat from the plane of the remainder of the body portion 42. A pair of fingers 50 extend normally outward from the section 48 and are similar to the fingers 28 including cylindrical fuse engaging portions 52, but omitting structure analogous to the flanges 38 of the upper clip 14. Rather than extending from the sides of the body portion, one of the fingers 50 extends from the end of the section 48 which is the extremity of the body portion and the other finger 50 is struck out of the U-shaped offset 46 and extends from the inner edge of the section 48. An abutment finger 54 extends outwardly from the section 48 and is

substantially normal to both the body portion and the fingers 50. The abutment finger 54 is provided with an offset 56 to provide resiliency and to position an abutment surface 58 terminating in a cam surface 60, adjacent to the lower edges of the fingers 50.

Mounting structure for the clips 14 and 16 is shown in Fig. 2 and includes a sheet metal bracket 62 having an apertured flange 64 which may be secured to the bracket 12 shown in Fig. 1. Adjacent to the flange 64 and perpendicular thereto is a side wall 66. A second side wall 68 is spaced from the side wall 66 by a wall 70 and is provided with a cut-out portion 72 to accommodate the U-shaped offset 46 of the lower clip 16. A flange 74 extends perpendicularly from the side wall 68. The flange 74 is apertured to receive a mounting screw 76 which cooperates with the aperture 26 in the upper clip 14 to secure the clip in place. A washer 78 may be provided beneath the head of the screw 76. In Figure 3 it may be seen that the finger 40 overlies the edge of the flange 74 to preclude rotation of the clip 14 about the screw 76.

An insulating member 80 fits against the wall 70 between the wide walls 66 and 68 and may be secured to the wall 70 by means such as rivets 82. The insulating member 80 is provided at each end with an extending tongue 82 which frictionally engage the edges of slots 84 in the cover or box 10 to secure the box on the bracket 62. It is to be understood that additional electrical equipment such as a relay could be mounted on the bracket 62 and within the box 10, but that this invention is not concerned with such equipment. A cross-shaped connecting member 85 is secured to the insulating member 80 adjacent to the top thereof by means such as rivets 86. The bracket 62 is apertured in the vicinity of the rivets 86 as the connecting member 85 must have no electric connection with the bracket 62. One arm of the member 85 extends upwardly and is provided with an aperture 88 with a helical edge similar to the aperture 20 previously described in order to coat with a screw to secure a lead wire 90. The lower leg 92 of the connecting member 85 is slightly offset from the remainder of the member so as to be spaced from the insulating member 80. The leg 92 and the insulating member 80 are provided with aligned apertures. The clip 16 is placed with the body portion 42 against the insulating member 80 and beneath the leg 92 and is secured in this position by a screw 94 extending through the aperture 84 and through the aligned apertures in the insulating member 80 and leg 92. The screw is retained by a nut 96 on the other side of the insulating member 80, it being understood that the bracket 62 is apertured or relieved in the

vicinity of the nut 96 to preclude electrical contact between the clip 16 and the bracket 62. With the clips mounted as just described, an elongated tubular fuse 98 having metal contacts 100 at each end, may be readily inserted in the clips as shown in Figures 3 and 4. The cam surfaces at the tips of the clip fingers facilitating positioning and the inherent resiliency of the metal fingers insure a good electrical contact between the clips and the fuse.

With the integral one-piece construction of each fuse clip herein disclosed, better and more enduring electric contact is insured than is possible with prior fuse clips of multi-piece construction. Additionally, the fuse clips herein disclosed may be more rapidly and economically manufactured than those heretofore known.

Although a specific illustration of my invention has been shown and described, it is to be understood that I do not intend to be limited thereby, but only by the following claim.

I claim:

A unitary fuse retaining clip structure comprising an elongated strip of sheet metal, a pair 25 of opposed sheet metal fingers integral with and extending substantially normally to said strip substantially at one end thereof for receiving and resiliently gripping one end of an elongated tubular fuse arranged at right angles to said elongated strip, at least one of said fingers being struck out from within the peripheral margin of the strip, means of limited cross section compared to the width of the strip on the end of the strip opposite the fingers for coaction with a workpiece to prevent rotation of the clip structure relative to the workpiece, said strip having an aperture intermediate said coacting means and said fingers adapted to receive a fastener to secure the clip structure to a workpiece, and abutment means integral with and extending substantially normally to said strip and said fingers across one end of the space included by said fingers to limit longitudinal movement of a fuse.

HAROLD H. McMAHON.
